[57] ABSTRACT

A filtering system for removing waste products released during the operation of drum-type pyrographic recorders, such as electroresistive recorders, comprises a filter cartridge which is sealed in a housing between a drum length funnel and the inlet side of a blower. The face of the funnel is in close proximity to the surface of the drum and is apertured so that a partial vacuum is maintained in the immediate area of the drum and along substantially its entire length, while localized separation of the recording medium from the drum is effectively precluded. The partial vacuum causes the waste product laden air to be drawn through the filter cartridge where the solid contaminants are trapped in a first stage and the gaseous contaminants are neutralized in a second stage.

FIG. 2

FIG. 1

FILTERING SYSTEM FOR PYROGRAPHIC RECORDERS

BACKGROUND OF THE INVENTION

This invention relates, generally, to filters for suppressing the waste products released during pyrographic recording and, more particularly, to filters for drum-type electroresistive recording equipment.

As is known, one of the more widely utilized species of pyrographic recording is an electroresistive process in which an image is formed by relying on the current flow between a stylus and a conductive layer of a recording medium to burn away localized areas of an overcoating on the recording medium, thereby exposing a contrasting underlayer in an image configuration. As a general rule, this process is carried out with relative motion between the stylus and the recording medium so that the stylus traverses the recording medium in accordance with a predetermined scanning pattern. For example, the electroresistive printing process has been used for several years with substantial success in what is known as the Xerox 400 Telecopier facsimile transceiver, which is manufactured and sold by Xerox Corporation. In that unit, the electroresistive recording paper is wrapped around a rotating drum and the stylus is mounted on a carriage which travels axially of the drum, with the result that there is a substantially helical scanning pattern. Hence, almost any desired image may be formed simply by controlling the voltage applied to the stylus as a function of time, or in other words, as a function of the position of the stylus relative to the recording medium. Indeed, the art of electroresistive recording has progressed to the point that shading of the image can be achieved by additionally controlling the magnitude of the voltage applied to the stylus. For that reason, the aforementioned 400 Telecopier transceiver is generally recognized as having a so-called "gray scale" capability.

Unfortunately, electroresistive recording is accompanied by the release of waste products, including aromatic gases, visible smoke, and particulate matter. The aromatics are responsible for objectionable odors, while the smoke and the particulate matter cause a residue to be deposited on the equipment. Analysis of a typical electroresistive recording process has led to a tentative conclusion that the major gaseous components evolving are carbon monoxide; ethane; 1, and 2-butenes; and n-butylmethacrylate, with the methacrylate being the strongest and most objectionable of the aromatics. The particulate matter, on the other hand, is believed to principally be small, light-weight ashes.

Others have previously proposed filters for suppressing such waste products. For example, U.S. Pat. No. 3,697,691, which issued on Oct. 10, 1972, purports to describe a filter for removing carbon particles and gas efflux as an image is electroresistively formed by a drum-type facsimile machine. However, the prior attempts to solve the problem have not fully been satisfactory for a number of reasons, including the relative complexity of the filtering equipment that has been suggested, the relatively short life span of the filtering elements used in that equipment, the high pressure drop which occurs across such filtering elements, and the failure to make full allowance for the turbulent environment in which the filtering is taking place.

SUMMARY OF THE INVENTION

Thus, the primary aim of the present invention is to provide a relatively economical and efficient filtering system for suppressing, if not completely eliminating, the waste products that are released during the operation of drum-type pyrographic recorders, including electroresistive recording equipment.

In keeping with that goal, a general object of this invention is to provide a filtering system which is especially well suited for use with such recorders, as measured by the ability of the system to remove gaseous and solid contaminants from the area immediately adjacent the drum and by the input energy required by the system to effect the filtering action.

More particularly, one of the important objects of the subject invention is to provide a filtering system which is particularly adept at removing waste products from the area immediately adjacent the drum of such a recorder, despite the turbulence of the air flow in that area. Another of the important objects is to provide a filtering system which not only supplies the desired filtering action, but which also aids in countering the centrifugal forces which act on the recording medium in such a recorder and which, if uncountered, would upset the recording process by separating the recording medium from the drum. A more detailed related object is to provide a filtering system with a special configuration which not only improves the filtering action that is obtained, but which also aids in retaining the recording medium against the drum, thereby yielding a highly beneficial synergistic effect.

A further object of the present invention is to provide a filtering system which, in addition to having the aforementioned characteristics, is relatively simple and economical to manufacture and service. A related object is to provide a filtering system of the foregoing type which has relatively few moving parts and relatively long lived filtering elements and, therefore, relatively minimal maintenance requirements.

Still another object of the present invention is to provide a filtering system of the foregoing type which may be stored for extended periods of time without appreciable loss of efficiency.

Consistently with the above stated objects, the filtering system here disclosed comprises a filtering cartridge which is sealed between an elongated funnel and the inlet side of a suitable air moving device, such as a centrifugal blower. To remove the waste products which are released during the operation of a drum-type pyrographic recorder and to aid in countering the centrifugal forces acting on the recording medium, the funnel is aligned in operation with the axis of rotation of the drum and its face, which has an aperture extending substantially the entire length of the drum, is in close proximity to the surface of the drum, with the aperture a few degrees in advance of the line of travel of the stylus along the drum. The blower, of course, creates a partial vacuum in the immediate area of the drum and along substantially the entire length thereof so that most of the waste products are ultimately drawn through the filtering cartridge, either immediately after being released or at some later time, depending upon the unpredictable interaction between the waste products and the turbulent air flow in the area of the drum. The filtering cartridge is a two stage filter; with a first stage comprising a porous packing to trap airborne par-

ticulate matter, such as ashes, and the second stage having an activated carbon medium to neutralize gaseous contaminants. Baffles are included in the second stage to force the air flow through the activated carbon even if the carbon has settled during storage or other prolonged periods of inactivity of the filtering cartridge.

BRIEF DESCRIPTION OF THE DRAWINGS

Further objects and advantages of this invention will become apparent upon reading the following detailed description in conjunction with the attached drawings, in which:

FIG. 1 is a simplified, fragmentary perspective view of a portion of a pyrographic recorder embodying a filtering system constructed in accordance with the present invention; and

FIG. 2 is a simplified sectional view taken along the line 2—2 in FIG. 1.

DETAILED DESCRIPTION OF THE ILLUSTRATED EMBODIMENT

While the invention is described in some detail hereinafter with reference to an illustrated embodiment, it is to be understood that there is no intent to limit it to that embodiment. On the contrary, the intent is to cover all alternatives, modifications and equivalents falling within the spirit and scope of the invention as defined by the appended claims.

Turning now to the drawings, it will be seen that a drum-type pyrographic recorder 11, including a filtering system 12 embodying the present invention, has been diagrammatically depicted. In keeping with a more or less conventional configuration for pyrographic recorders, the recorder 11 comprises a rotatable drum 13 and a stylus 14. Typically in operation of such a recorder, a suitable recording medium (not shown) is wrapped around the drum 13 which, in turn, is rotated about its longitudinal axis at a predetermined rate as the stylus 14 is moved lengthwise of the drum 13 along a line substantially parallel to its axis of rotation. As a result, a substantially helical scanning pattern is generated with the result that the stylus 14 can be readily controlled to burn away localized areas of an overcoating on the recording medium, thereby exposing a contrasting underlying layer thereof in an image configuration.

For a more detailed understanding of the construction and operation of an exemplary pyrographic recorder with which the filtering system 12 can be advantageously utilized reference may be had to the electroresistive recorders comprised by the aforementioned, commercially available Xerox 400 Telecopier facsimile transceivers and the published literature pertaining thereto. Accordingly, attention is here focused primarily on the filtering system 12.

As shown, the filtering system 12 includes a filtering cartridge 15 which is sealed by a pair of gaskets 16 and 17 in a housing 18 between a funnel 19 and the inlet side of a suitable air moving device, such as a centrifugal blower 21. The face 22 of the funnel 19 is apertured as at 23 and the outlet or discharge side of the blower 21 is open to the atmosphere. Thus, the blower 21 creates a partial vacuum, thereby causing air to be drawn into the aperture 23 and through the cartridge 15 prior to being discharged to the atmosphere. As will be appreciated, the sealing gaskets 16 and 17 mechanically

stabilize the cartridge 15 and prevent any appreciable leakage of air through the spaces between the cartridge 15 and the housing 18.

In accordance with an important feature of this invention, the filtering system 12 serves a dual function or in other words, has a synergistic effect. That is, it not only removes the waste products that are released as an image is formed on the recording medium, but it also precludes any significant localized separation of the recording medium from the drum 13. In the Xerox 400 Telecopier transceiver, for example, there are four wipers (not shown) which are spaced at substantially equal angular increments about the periphery of the drum to cooperate with a gripper bar 24 in retaining the recording medium in contact with the drum despite the centrifugal forces which tend to cause a separation to occur. As here shown, however, the filtering system 12 permits one of the wipers to be eliminated while still retaining its function.

More particularly, to carry out the above noted functions, the funnel 19 is elongated and is mounted (by means not shown) so that its face 22 is maintained in close proximity to the surface of the drum 13; for example, within 0.05 inches or so thereof. Because of the relatively narrow gap between the surface of the drum 13 and the face 22 of the funnel 19, together with the elongated configuration of the funnel, local separation of the recording medium from the drum is effectively precluded. Moreover, advantage may be taken of the elongated configuration of the funnel 19 to optimize the filtering action. To that end, the aperture 23 is selected to have a length, as measured parallel to the axis of rotation of the drum 13, substantially equal to the length of the drum 13 so that a partial vacuum is constantly maintained in the immediate area of the drum along substantially the entire length. Preferably, the aperture 23 is just slightly in advance of the line of travel of the stylus 14, as measured in the direction of rotation of the drum. Nevertheless, some of the waste products that are released as an image is formed may, at least initially, be directed away from the aperture 23 as a result of the turbulent air flow which inherently occurs in the immediate area of the drum. Accordingly, it will be understood that one of the important characteristics of the filtering system 12 is that the filtering action is substantially independent of the position of the stylus 14, with the result that waste products may be captured, either as they are released or at some time later. Of course, transverse stiffening ribs 20 may be spaced at intervals along the face 22 of the funnel 19 without materially impairing the filtering action. The stiffening ribs 20 mechanically strengthen the funnel 19 and also enhance its wiper action.

As illustrated, the filtering cartridge 15 has an upstream chamber 25 filled with a porous packing 25a, such as a 6 ounce density, non-woven fiber, for trapping the solid contaminants carried by the waste product laden air that is drawn therethrough and a downstream chamber 26 filled with an activated carbon medium 26a, such as the Type 582 activated carbon manufactured and sold by Barnaby & Cheney, Inc., for neutralizing the gaseous contaminants. A relatively low pressure drop occurs across the filtering section 15 inasmuch as it is substantially coextensive with the aperture 23 and provides a generally straight through air flow path. Accordingly, the partial vacuum existing at the inlet side of the blower 21, which may be consid-

ered to be the input energy to the filtering system (of course that definition of the input energy normalizes for the wide spread in the efficiencies of the various commercially available blowers, ranging from relatively low cost, inefficient units to expensive but effective models), is efficiently transferred to the aperture 23.

The downstream chamber 26 is initially filled to capacity with the activated carbon medium and provision is made for preventing any appreciable depletion of the initial charge. For example, the front and rear of the chamber 26 may suitably be covered with respective screens 27 and 28 with a mesh size selected to preclude leakage of the activated carbon medium. Nevertheless, some settling of the activated carbon inherently takes place, especially during prolonged periods of inactivity or storage of the cartridge 15. Consequently, in keeping with one or more of the detailed aspects of this invention, baffles 31 are included in the chamber 26 to force the air passing therethrough to flow through the activated carbon even if settling has taken place. The critical area of the compartment 26 is, of course, the upper portion thereof since that is where a free space might be found. However, to simplify the tooling used in the manufacture of the chamber 26 and to avoid any definite upper side-lower side pre-orientation of the cartridge 15, the chamber 26 is preferably symmetrical and, therefore, has baffles 31 extending inwardly from both its upper and lower faces.

The life span of the non-woven and activated carbon filtering elements depends in significant part on their depth. In the interest of completeness, therefore, it is perhaps worth mentioning that a filtering cartridge having an upstream chamber 25 approximately 1.2 inches deep and a downstream chamber 26 approximately 2.5 inches deep has been tested and that the test results have indicated that the non-woven packing requires replacement just about twice as often as the activated carbon medium. Specifically, it is believed that a practical maintenance procedure is to replace the packing 25a after approximately 2,000 recordings have been made and to then replace the complete cartridge 15 after another 2,000 recordings have been made.

CONCLUSION

In view of the foregoing, it will be now appreciated that a relatively economical and efficient filtering system for suppressing the waste products that are released during the operation of a drum-type, pyrographic recorder has been provided. The filtering system has relatively few moving parts and relatively long lived filtering elements and is, therefore, fairly simple to maintain. Moreover, it not only removes most, if not all, waste products that are released during the recording process despite the turbulent air flow around the drum, but it also aids in countering the centrifugal forces acting on the recording medium to assist in retaining the recording medium in contact with the drum.

What is claimed is:

1. In combination with a pyrographic recorder having a stylus for forming an image on a recording medium carried by a rotatable drum, a filtering system for suppressing waste products released while said image is formed; said filtering system comprising a funnel hav-

ing a face adjacent said drum with a substantially drum-length aperture extending longitudinally of said drum, said funnel positioned to prevent any localized separation of said recording medium from said drum, an air moving device having an inlet side and an outlet side, and a filtering means interposed between said funnel and the inlet side of said air moving device so that a partial vacuum is constantly maintained during operation of said system in an area immediately adjacent said drum, thereby causing waste product laden air to be drawn through said funnel to pass through said filtering means whereby waste products are removed therefrom.

2. The combination of claim 1 wherein said filtering means comprises a first stage for removing solid waste products and a second stage for neutralizing gaseous waste products.

3. The combination of claim 2 wherein said second stage is charged with an activated carbon medium and includes means for ensuring that any air passing through said filtering means flows through said medium even after extended periods of inactivity of said filtering means.

4. In combination with a facsimile unit having a stylus for electroresistive printing on a recording medium carried by a rotatable drum as the stylus travels axially of the drum, a filtering system for suppressing waste products released while said printing is performed, said filtering system comprising a funnel having a face positioned in close proximity to said drum for precluding any appreciable localized separation of said recording medium from said drum and a drum length aperture in said face, an air moving device having an inlet side and a discharge side, and a filtering means interposed between said funnel and the inlet side of said air moving device, whereby a partial vacuum is constantly maintained during operation of said system in an area immediately adjacent said drum along substantially the entire length thereof to cause waste produce laden air to be drawn through said aperture and to pass through said filtering means so that waste products are suppressed.

5. The combination of claim 4 wherein said drum has a predetermined direction of rotation, said stylus is moveable axially of said drum along a predetermined line of travel, and said aperture is slightly in advance of said line of travel as measured in the direction of said rotation.

6. The combination of claim 4 wherein said filtering means comprises a first stage filled with a replaceable porous packing material for trapping solid components of said waste products and a second stage charged with an activated carbon medium for neutralizing gaseous components of said waste products.

7. The combination of claim 6 wherein said second stage includes baffles for preventing air from traveling therethrough without passing said activated carbon medium.

8. The combination of claim 6 wherein said drum has a predetermined direction of rotation, said stylus is moveable axially of said drum along a predetermined line of travel, and said aperture is slightly in advance of said line of travel as measured in the direction of rotation of said drum.
